UNITED STATES PATENT OFFICE

2,535,620

METAL SHINGLE AND STRIP

Alfonso Alvarez, Jr., Upper Montclair, N. J.

Application April 21, 1947, Serial No. 742,903

6 Claims. (Cl. 108—17)

1

This invention relates to shingles and means for applying shingles to a wall.

It is an object of this invention to provide an improved metal shingle and a shingle supporting strip, which are particularly adapted for use on buildings in which the walls are constructed of more or less flimsy material, hardly sufficiently strong to support the shingles or shingle supporting strips by nailing the shingles and strips to the building wall material. The shingle supporting strips are adapted to be nailed to the vertical or horizontal studs which support the building wall.

Another object of this invention is to provide an improved metal shingle of the kind to be more particularly described hereinafter, having an insulating body fixed to the metal shingle to provide for the insulation of the building wall.

Another object of this invention is to provide an improved metal shingle and attaching means therefor whereby a strong and durable fireproof shingle is provided and may be readily attached in a speedy manner.

Still another object of this invention is to provide an improved shingle supporting strip which will support the lower end of the shingles above this strip and secure the upper end of the lower shingles in such a manner that the shingles are securely fixed to the building and may be readily applied so that the shingles may be attached much quicker than the conventional means for fastening shingles to a building wall.

With the above and other objects in view, my invention consists in the arrangement, combination and details of construction disclosed in the drawings and specification, and then more particularly pointed out in the appended claims.

In the drawings,

Figure 1 is a fragmentary front elevation of a building wall composed of shingles and building strips constructed according to an embodiment of this invention.

Figure 2 is a vertical section taken on the line 2—2 of Figure 1.

Figure 3 is a transverse section taken on the line 3—3 of Figure 1.

Figure 4 is a rear elevation of a single shingle.

Figure 5 is a perspective view of a shingle supporting strip.

Figure 6 is a fragmentary section of one side of a shingle.

Figure 7 is a fragmentary section of the other side of the shingle for engagement with the side shown in Figure 6.

Figure 8 is a fragmentary front elevation of

2

a building wall composed of a modified form of shingles, and

Figure 9 is a fragmentary transverse section taken on the line 9—9 of Figure 8.

Referring to the drawings, the numeral 10 designates generally a building wall of a building, wherein the wall is made of the cellulose material or thin wood customarily used in this type of building fabrication.

A shingle supporting strip 11 and metal shingle 12 constructed according to an embodiment of this invention, are fixed to the building wall 10 by nails 14 or other suitable fastening devices, in the relation shown in Figure 2.

The shingle 12 is formed of an outer strip or plate of sheet metal 15, having a strip of insulating material 16 fixed on the rear side thereof. The shingles 12 may be of any size, as the size of conventional shingles or may be elongated to extend either between adjacent vertical studs of a building or any other suitable length.

The metal body 15 is bent inwardly at its lower end to provide a lower wall 17, and then reverted to provide a substantially U-shaped lower end 18. The U-shaped lower end 18 is so constructed that the body or plate 15 forms one arm thereof, the lower wall 17 forms the bight, and the reverted section 19 forms the other arm. The free end of the arm 19 is reverted again inwardly to provide a downwardly extending flange 20. The upper end of the body 15 terminates along with the upper edge of the insulating body 16.

One side of the body 15 is bent back and deverted to provide a U-shaped keeper 21. The body 16 is adapted to abut the inner side of the inner arm 22 of the keeper 21. The outer arm 24 of the keeper 21 is spaced slightly outward from the arm 22 to provide a space 25 between the arms. The other side of the plate 15 is bent backward substantially parallel to the keeper 21 to form a flange 26. The flange 26 is spaced slightly outwardly away from the side edge of the insulating body 16.

When the shingles 12 are assembled they are interlocked along their abutting edges by the flanges 26 engaging between the arms 22 and 24 in the space 25 of an adjacent shingle 12.

For supporting the shingles 12 on the wall 10, there is provided an improved shingle supporting strip 11. The shingle supporting strip 11 is formed of an elongated strip of sheet metal or other suitable material, and is either bent or otherwise formed to the desired shape. When formed of sheet metal the strip 11 is formed with a flat wall abutting surface 30, being bent out-

wardly at right angles to provide an outwardly extending flange 31 at the lower end of the wall abutting strip 30.

The strip 11 is then bent downwardly and reverted at the outer end of the flange 31 to form a U-shaped keeper 32. The U-shaped keeper 32 is formed with substantially vertical and parallel arms 34 and 35, connected by a lower bight 36. Longitudinally spaced apart openings 37 are formed in the wall abutting portion 30 of the strip 11, through which the nails 14 are adapted to engage for securing the strip 11 to the wall. The flange 31 of the strip 11 is of a length substantially the same as the thickness of the shingle represented by the metal body 15 and the insulating body 16 so that the upper end of a shingle may be clamped to the wall 10 by the inner arm 34 of the keeper 32.

In Figure 8 there is shown a modified form of this invention in which the sheet metal shingle is formed with a metal outer body 15a, which is corrugated or ribbed. The ribs 40 of the shingle 12a add stiffness and strength to the shingle and provide for the improved appearance thereof.

In the use and application of these shingles, the shingle strips 11 are secured to the wall 10 near the lower edge first. The shingles 12 are then engaged with the supporting strip 11 by engaging the flange 29 over the outer arm 35 of the keeper 32 for supporting the lower end of the shingles. A complete row of shingles is thus applied to the wall 16 and then the strip 11 is fixed to the wall at the upper edge of this row of shingles. The upper strip 11 is fixed so that the upper edge of the shingle 12 is clamped between the wall 10 and the arm 34 with the flange 31 covering the upper edge of the lower shingles. In this manner an efficient insulating and weather proof wall is provided which may be constructed in a minimum amount of time.

I do not mean to confine myself to the exact details of construction herein disclosed, but claim all variations falling within the purview of the appended claims.

What I claim is:

1. An improved shingle comprising a metal body, insulating material fixed under one surface of said body, a reverted U-shaped lower end on said body encompassing the lower edge of said insulating material, and a reverted downwardly extending shingle attaching hook on the inner edge of said U-shaped lower end of said body.

2. An improved shingle comprising a metal body, a U-shaped lower edge on said body, said body forming one arm of said U-shaped edge, the other arm of said U-shaped edge being reverted forming a depending supporting flange on said shingle, a flange on one side edge of said body, and a U-shaped keeper on the opposite side edge whereby adjacent shingles may be interlocked at their adjacent side edges.

3. An improved metal shingle comprising a corrugated body, a reverted U-shaped lower edge on said body, a depending supporting flange on the inner arm of said lower edge, an inwardly extending flange on one side edge of said body, and an outwardly opening U-shaped keeper on the opposite side edge whereby adjacent shingles may be interlocked at their adjacent side edges.

4. An improved shingle comprising a metal body, a reverted U-shaped lower edge formed on said body, a supporting flange depending from the free edge of the inner arm of said U-shaped lower edge, an inwardly extending flange on one side edge of said body, and an outwardly opening U-shaped keeper on the opposite side edge whereby adjacent similar shingles may be interengaged at their adjacent side edges.

5. An improved metal shingle comprising a flat body, a reverted U-shaped lower edge formed on said body, a supporting flange reverted from the upper edge of the free arm of said U-shaped edge, an inwardly extending flange on one side edge of said body and an outwardly opening U-shaped keeper on the opposite side edge whereby adjacent similar shingles may be interengaged along their adjacent side edges.

6. An improved metal shingle as set forth in claim 5, including insulating material fixed on the inner surface of said body.
